CLAIM

The ornamental design for a socket for extension cord, as shown and described.

DESCRIPTION

FIG. 1 is a top front right-side perspective view of a socket for extension cord, showing my new design;

FIG. 2 is a bottom front left-side perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The socket for extension cord is shown with a symbolic break in its length. The appearance of any portion of the article between the break lines forms no part of the claimed design.

The broken lines depict portions of the socket for extension cord that form no part of the claimed design.

1 Claim, 8 Drawing Sheets(56)
